(57) **CLAIM**

The ornamental design for a magnetic metal detector with extendable wand, substantially as shown and described.

DESCRIPTION

FIG. 1 is a perspective view of the detector with the wand extended;

FIG. 2 is a perspective view of the detector with the wand retracted;

FIGS. 3A and 3B are left side views with the wand extended and retracted, respectively;

FIGS. 4A and 4B are front views with the wand extended and retracted, respectively;

FIGS. 5A and 5B are right side views with the wand extended and retracted, respectively;

FIGS. 6A and 6B are back views with the wand extended and retracted, respectively;

FIG. 7 is a top view; and,

FIG. 8 is a bottom view.

FIGS. 1-2 and 7-8 are enlarged relative to FIGS. 3-6 in order to better show the details.
